UNITED STATES PATENT OFFICE.

HARRY PERRY, OF BROOKLYN, NEW YORK, ASSIGNOR TO METROPOLITAN-COLUMBIA MFG. CO., INC., A CORPORATION OF NEW YORK.

DESIGN FOR AN ARM FOR CHANDELIERS OR SIMILAR ARTICLES.

Application filed December 19, 1925. Serial No. 15,795. Term of patent 3½ years.

To all whom it may concern:

Be it known that I, HARRY PERRY, a subject of the King of Great Britain, and a resident of Brooklyn, county of Kings, and State of New York, have invented a new, original, and ornamental Design for Arms for Chandeliers or Similar Articles, of which the following is a specification, reference being had to the accompanying drawing, forming a part thereof.

In these drawings:

I claim:

The ornamental design for an arm for chandeliers or similar articles, substantially as shown.

HARRY PERRY.
